UNITED STATES PATENT OFFICE.

RALPH W. HARTWELL, OF DAVENPORT, IOWA.

ICE-BOX.

1,080,551.

Specification of Letters Patent.

Patented Dec. 9, 1913.

Application filed February 19, 1912. Serial No. 678,445.

To all whom it may concern:

Be it known that I, RALPH W. HARTWELL, a citizen of the United States, residing at Davenport, in the county of Scott and State 5 of Iowa, have invented certain new and useful Improvements in Ice-Boxes, of which the following is a specification, reference being had therein to the accompanying drawing.

10 This invention relates to preserving receptacles for fish and other game and has for its object the production of an efficient receptacle which may be easily carried.

Another object of this invention is to provide 15 an efficient means for emptying the receptacle or aperture in the bottom thereof and means to readily close said aperture.

With this and other objects in view, the invention consists in general of certain novel 20 constructions, arrangements and combinations of parts as will be hereinafter fully described, illustrated in the accompanying drawings, and specifically claimed.

In the drawings: Figure 1 is a perspective 25 view of the receptacle having a portion of the lid open. Fig. 2 is a longitudinal section of the receptacle. Fig. 3 is a top plan view thereof with the cover removed. Fig. 4 is an enlarged sectional view through the 30 drain valve formed in the bottom of the receptacle. Fig. 5 is a detail perspective of one of the game containing cans.

Referring to the accompanying drawings by numerals 1 designates the body of the 35 receptacle which is preferably rectangular in shape. The receptacle is covered upon its outer side with a strip of cloth 2 which cloth is shellacked so as to make the same water-proof. The inner face of the body 1 40 is first lined with a strip of asbestos 3 and next with a layer of felt 4 and a third lining of zinc 5. This lining, as above described, extends over the entire surface of the receptacle and the cover 6 is in like manner 45 provided with a lining similar to the body portion of the receptacle. The cover 6 is provided with a shouldered portion 7 which shouldered portion is provided with a fabric or felt covering 8 which forms an 50 efficient sealing means around the entire edge of the cover 6.

The cover 6 comprises a pair of sections secured together by means of hinges 9 and these sections 6 have, upon their abutting 55 edges, felt linings 10 forming an efficient air

tight seal between the abutting ends of said sections. A handle 11 is secured to the sections 6 by means of binding straps 12.

Latch members 13 are secured to each side of the receptacle 1 and engage coöoperating 60 members 14 carried by the top 6 for holding the top in firm engagement with the body 1. These latch members 13 are so placed upon the receptacle 1 as to engage the outer ends of each section of the top and also to engage 65 each section upon the sides thereof. Corner binding members 14^a are placed upon the receptacle 1 as illustrated in Fig. 1 for shielding the corners against injury.

The handle 11 is preferably formed of 70 leather or similar material so as to allow the same to be bowed for facilitating the raising of one of the sections of the top while the other section is firmly secured to the body 1. When it is so desired one section of the top 75 may be raised to the position as shown in Fig. 1 and while this section is in such a position it will be obvious that the handle 11 will form a brace for the top for holding the open section in a set position. 80

Two game receiving receptacles 15 are provided in connection with the present device and these receptacles are preferably carried at the ends of the receptacle 1, as illustrated in Figs. 2 and 3. If it is so desired ice may 85 be carried within the receptacle between the two cans 15. The cans 15 are provided upon two of their corners with braces 16 which braces hold the cans in their proper rectangular shape so as to allow the cans to be easily 90 inserted within the receptacle 1 and also avoiding the danger of destroying the shape of the cans and making it possible to place the cans 15 within the receptacle 1.

The receptacle 1 is provided with a socket 95 17 formed upon the body thereof which socket is lined by means of a casing 18, held in place by screws passing through a flange 18' at the outer end of the casing. This casing 18 fits against the thickened portion 5' 100 formed upon the lining 5 and is provided with an aperture 19 through which extends a sleeve 20 leading from the thickened portion 5' and internally threaded for receiving a threaded stem 21. This threaded stem 21 is 105 provided with a milled head 22 for facilitating the rotation of the stem 21 within the sleeve 20. The stem 21 is provided with a longitudinally extending aperture 23 which terminates in a discharge aperture 24. 110

It will be obvious that when it is desired to drain the receptacle 1 the cans 15 may be shifted or removed from the receptacle 1 and the stem 21 of the valve moved downwardly 5 so as to allow the discharge aperture 24 to be clear of the sleeve 20. The receptacle can then be drained of the water contained therein by the same passing through the hollow stem 21 and out through the discharge aperture 24. As will be seen by carefully considering Figs. 2 and 4 the valve device will be entirely shielded by the casing 18 and will not be likely to become fractured by coming into engagement with foreign objects. It 10 will, of course, be obvious that the valve may be closed by screwing the stem 21 upward 15 within the sleeve 20.

From the above description it will be obvious that I have produced a portable ice box 20 wherein fish and other game may be placed and preserved. This receptacle is especially adapted for a hunter or fisherman where it is desired to keep the game fresh until reaching home. By the use of the receptacle as 25 above described it will be obvious that the game may be placed within the cans 15 and in view of the fact that an air tight recep-

tacle has been produced game will be preserved in good condition.

Having thus described my invention, what 30 is claimed is:

A device of the character described comprising a waterproof receptacle, a cover therefor, said receptacle having a portion of its bottom in the form of a recess, said bottom having a drain outlet tube disposed centrally within the recess, said tube being internally threaded, said tube terminating short of the outer surface of the bottom of the receptacle, a protecting casing fitting the 40 recess and having its top provided with an opening through which the tube depends, the casing being provided with an out-turned base flange that is fastened to the outer surface of the bottom of the receptacle, and an 45 externally threaded hollow plug engaging the threads of the tube and provided with a lateral discharge outlet.

In testimony whereof I hereunto affix my signature in presence of two witnesses.

RALPH W. HARTWELL.
